Patented Jan. 6, 1970

216,427

TELEPHONE HANDSET SUPPORT

Henry Dreyfuss, South Pasadena, Calif., Donald M. Genaro, Haworth, N.J., Gordon E. Sylvester, Jamaica, N.Y., and Stephen W. Walden, Morral Township, Shelby, Ind., assignors to Bell Telephone Laboratories, Incorporated, Murray Hill, N.J., a corporation of New York

Filed Dec. 31, 1968, Ser. No. 15,166

Term of patent 14 years

Int. Cl. D14—03

U.S. Cl. D26—14

FIG. 1

FIG. 2

FIG. 3

FIG. 4

FIG. 5

FIG. 1 is a front view of a telephone handset support showing our new design;

FIG. 2 is a front perspective view;

FIG. 3 is a side view of the handset support in an alternate position;

FIG. 4 is a top plan view of the handset; and

FIG. 5 is a bottom plan view thereof.

The broken lines are shown for illustrative purposes only.

We claim:

The ornamental design for a telephone handset support, substantially as shown and described.
